CONTROLLED FLUID DELIVERY SYSTEM

Judson P. Smith, Cloquet, Minn., assignor to
 Wood Conversion Company, St. Paul, Minn., a
 corporation of Delaware

Application December 2, 1946, Serial No. 713,602

15 Claims. (Cl. 302—17)

1
 The present invention relates to systems for fluid delivery, and especially pneumatically conveying and depositing solid material, and in particular to systems for pneumatically packing insulating particles into an insulating space. The invention has general reference to such systems and to electrically operated controls therefor.

Recently systems have been developed for pneumatically packing insulating material, such as fiber, into insulating spaces exemplified by refrigerator cabinets. The systems referred to have been developed for use in assembly-line manufacturing operations wherein cabinets, or doors therefor, to be filled move in succession past a filling station. In such operations the cabinet or other article to receive particles, such as insulating fiber, is arrested at the station for and during the filling operation. Certain mechanical operations may or may not be manually required, but where this is not so the operation may be completely automatic after initiation.

The present invention provides apparatus for such operations and includes a variety of controls which may be pneumatic, mechanical or electrical controls, and which are inter-related so that the system may be controlled manually, entirely automatically, or semi-automatically, as conditions may require, and as will appear hereinafter.

It is the general object of the invention to provide a pneumatic conveying and depositing system which operates in a cycle, and which has controls enabling an operator to initiate, and to continue if necessary, an operation, and to stop an operation either manually or automatically to place the equipment in condition for a repetition of the cycle.

It is a particular object of the invention to provide a multiplicity of coordinated mechanical and electrical controls of such character that the system may be operated manually, completely automatically, or semi-automatically.

It is a particular object of the invention to include in the system mechanical equipment and controls therefor requiring only the manual initiation of a cycle to cause the system to complete a cycle and ready itself for a second cycle.

It is also an object of the invention to establish a semi-automatic operation such that a cycle is initiated by a manual control and automatically carried to a point where the operation stops for the conduct of a manual step, and then continues by manually initiating the continuance for carrying it to automatic closure of the cycle and readiness for a second such cycle.

Other objects are to establish particular inter-related controls as will be hereinafter set forth.

2
 Numerous other and ancillary objects and advantages of the invention will appear hereinafter from the accompanying description of an exemplary embodiment of the invention as it has been adapted for the filling of insulated containers in an assembly-line operation.

In the drawings, Fig. 1 represents more or less diagrammatically an assembly of the principal mechanical devices and certain controls associated therewith.

Fig. 2 is a wiring diagram of electrical controls for the equipment of Fig. 1 as it is arranged to function for complete automatic cycling.

Figs. 2a and 2b are modifications of the wiring diagram of Fig. 2 which modifications appear effective graphically when superimposing the dotted-line structures of Fig. 2 and Fig. 2a, and of Fig. 2 and Fig. 2b.

Fig. 3 is a wiring diagram for a semi-automatic operation in which the cycle stops for performance of a manual step and for continuance by manual initiation for continuance.

Figs. 3a and 3b are modifications of the wiring diagram of Fig. 3 which modifications appear effective graphically when superimposing the dotted line structures of Fig. 3 and Fig. 3a, and of Fig. 3 and Fig. 3b.

Fig. 4 is a wiring diagram for a control system which can be shifted manually for operation in accordance with the circuits of Fig. 2 or in accordance with the circuits of Fig. 3.

Figs. 4a and 4b are modifications of the wiring diagram of Fig. 4 which modifications appear effective graphically when superimposing the dotted-line structures of Fig. 4 and 4a, and of Fig. 4 and Fig. 4b.

The invention may be applied to any system for delivering a fluid stream, in which system it is desired to deliver, then to stop, and then to repeat such operation. The fluid may be liquid such as water, milk, soups (in canning), or fuel, such as oil or gasoline. The fluid may be a gas, such as air, and such gas may also be used as a vehicle to convey solid particles suspended therein, such as grain, comminuted coal, mineral, or insulating material. To illustrate the invention in its preferred and more complicated aspects, there is shown a system including means to feed fiber, means to provide a stream of air, and controlled means to feed the fiber into the air so that a fiber-in-air suspension is formed.

It is therefore to be understood that the system is not to be considered as limited in its application to the illustrative example of delivering fiber to spaces to be insulated, as in refrigerator cabinets. The following description is therefore in

specific reference to the presently preferred embodiments of the invention.

The invention pertains to systems not entirely automatic from cycle to cycle, but automatic within a cycle, and such as to require manual initiation. A particular feature of the invention is a prolonged manual control over the initiation until a point of readiness for effectual functioning is attained. Until readiness is reached the system remains subject to manual control, preferably as a prolonged manual initiating action. In the system there is a readiness-responsive device which operates to take the control away from the operator and to continue it automatically to the desired point of completion. The readiness-responsive device may also perform other acts in addition to taking control from the operator, such for example as to initiate feed of solid material into a flowing air stream, where the flowing of the stream is an indication of readiness.

Briefly, the mechanical operations to be performed constitute the introduction of article form material into air to produce a suspension in air, the conveyance of the air suspension of such material to a point of discharge or deposition and the continued discharge or deposition of the same for a time extending to what is herein referred to broadly as a "cut-off" point. The cut-off point may be the stopping point for the operation determined arbitrarily and thereby manually registered in the system, or determined automatically by some physical condition encountered during the operation which physical condition may effect an automatic registration in the system of the cut-off point. The manual or the automatic registration in the system of the cut-off point is effective to stop the operation and to restore the system in part or entirely automatically to a condition for a new cycle of operations.

In the particular and preferred embodiment of the preferred invention the solid material is fibrous thermal insulation and it is drawn into the suction intake of a fan blower which discharges a suspension of fiber in air through its discharge outlet to a filling station. The filling station involves means to connect a receptacle to be filled, such as a refrigerator cabinet to be thermally insulated, with a fixture adapted to the cabinet and to the intended operation, so that discharge of the fiber suspension into the connected fixture and receptacle results in depositing insulating fiber in its intended space. The filling station also includes means to vent the air from the space being filled. This quickly results in filling the space to be insulated with fiber. Further, the arrangement is such that when the space is so filled, the cut-off point is reached, and in the preferred operation the cut-off automatically registers, stops the operation, and initiates return to initial condition of readiness for another cycle. This will all be clear from the following description of the illustrated embodiment of the invention to accomplish the foregoing purposes.

In Fig. 1, numeral 10 represents an opened previously-wired bale of fiber resting on an endless conveyer belt 11 operating over the pulleys 12 and 13, one of which is suitably driven, as by means such as the electric motor 14. The belt 11 travels slowly in order gradually to feed the bale 10 to a bale-breaking device such as a rotor 15 within a housing 16. The rotor 15 is operated by powered means 17. The bale-breaking means 15 is effective to disintegrate the compacted fiber of bale

10 into a loose and fluffy form which is discharged from the housing 16 through outlet 18 opening into an intake conduit 19 of a fan blower 20. The arrangement of the foregoing parts is such that both the blower 20 and the rotor 15 may operate continuously so that by arresting the travel of the conveyer 11 and the bale 10 into the housing 16, the feeding of fluffed fiber to the blower 20 is also arrested. Since the invention involves means to stop the feeding of the fiber or like material, it is preferred to have such means operate upon the motor 14 to arrest the feeding mechanism. This control will be later described.

The fan blower 20 discharges centrifugally and, as shown, discharges preferably downwardly from the blower 20 through the conduit 21 to a discharge or depositing or filling station at the lower end of conduit 21.

It is desirable to have flow control in the blower system. Such flow control is in the form of a valve or gate which functions to stop the delivery through conduit 21 of air by the fan 20 even though the fan may continue its rotation. Such a valve or gate may be placed either in the intake conduit 19 or in the discharge conduit 21, or in both places. Two such locations are shown, the gate 25 being in the inlet conduit 19 and the gate 26 being in the discharge conduit 21.

Where two gate valves are employed, as shown, they are preferably operated together and by the same controlling device, and they are preferably operated by fluid control, for example, by compressed air. Each valve has a gate 27 and a gate-holding chamber 28 in which the gate 27 is housed when the gate is in open position. The gate carries an operating stem 29 projecting from the gate housing 28 and movable into and out of said housing 28 to close and open the gate. The operating stem 29 is connected to a piston rod 30 having piston head 31 operating in cylinder 32. The two ends of the cylinder 32 have connection to a compressed air supply so that by introducing air into one connection and exhausting it from the other, the piston is moved to operate the gate. Numeral 34 represents the connection for supplying air to close the gate and numeral 35 represents the connection supplying air to open the gate. It is also to be observed that there may be a connection 36 between the connection 35 and the gate housing 28, so that when the gate is being opened and is open, an air stream passes through connection 36 into the gate housing and along into the blower system. This is described in my copending application, Serial No. 713,603, filed December 2, 1946, now Patent No. 2,544,054, for the purpose of keeping the gateways and seat free from fiber, and to avoid the accumulation of fiber in the free spaces of the gate valve where it would eventually impede its proper operation.

Further means for controlling the operation of the gate involve control of the air supply to the cylinder 32. The numeral 38 represents a pipe-line supply of air under pressure as a connection to a control-valve housing 39 which housing has discharge outlet 40. The illustrated control valve 39 is merely a conventional representation of any suitable valve for the purpose, and in such representation the diagrammatic rotary valve member 41 is moved to shift the air supply from one to the other of the connections 34 and 35 to the cylinder 32. Diagrammatically represented, the four said connections to the valve housing 39 are arranged 90° apart in the following order, 38, 35, 40 and 34. When the valve element 41 is in the full-line position

shown, air pressure passes through connection 34 to hold piston rod 38 connected to piston 31, out and hence hold the gate 21 closed. By turning the valve element 41 through 90° to dotted-line position 41a, the supply of air and the exhaust connection are shifted and the piston 31 is moved to open the gate 21 and to hold the gate open. The complete system of the present invention involves electrically controlled means to move the valve member 41 from one of its two positions to the other. Such control means is designated by the numeral 42 and has the electrical circuit 43 leading to it, which circuit is energized to open the gate 21.

The valve 26 in the discharge conduit 21 has a similar structure and operation and its parts are corresponding numbered, but with prime designations.

The discharge station may be such as to receive a receptacle to be filled, such as a refrigerator, and to establish operating connection to it. This is preferably accomplished by moving the receptacle onto a platform section which moves into a connecting position, preferably as a lift. Controlled means is provided for raising and lowering such a lift to effect connection of the receptacle to suitable fixture means on the end of discharge conduit 21. The lift is preferably operated by fluid pressure, such as pneumatic pressure. A diagrammatic illustration of a suitable station is shown in Fig. 1, involving an air-control valve which is generally similar to that employed for opening and closing the valves 25 and 26.

Numerical 45 represents a lift having a platform for a receptacle 46 thereon to be connected to a fixture 47 placed directly above the lift. The lift is carried by a piston having shaft 48 and head 49 operating in air-pressure cylinder 50, to both ends of which there are separate air-pressure connections 51 and 52. Numeral 53 is a diagrammatic representation of a valve casing having a rotary valve member 54 therein movable into full-line position shown and into dotted-line position 54a. An air-pressure supply connection 55 and an air discharge connection 56 are connected to the valve casing 53. The connections to the valve casing 53 are arranged in quadrants, as shown, in the following order 56, 52, 56 and 51. The valve member 54 is under the control of suitable operating means diagrammatically represented by the numeral 58 which is preferably, but not necessarily, an electrically controlled device having the circuit wires 59 leading thereto, which are energized to raise the lift 45. In operation, mere turning of the valve member 54 from one position to the other moves the lift from one to the other of its upper and lower positions, and holds it so moved.

The fixture 47 may partake of many designs according to the character of the article 46 to be filled. Merely as a conventional indication of one of the preferred arrangements, the receptacle 46 is shown in cross-section as a refrigerator cabinet minus its food compartment, and as having just been filled with insulation 10a. The filled receptacle 46 is shown as it is being retracted from the fixture 47 which includes a screen-walled dummy portion 60 corresponding in shape to the food compartment which will thereafter be set in the recess indicated as formed in the insulation 10a by the dummy 60. Said screen dummy 60 is attached to and forms part of the fixture 47. Within the fixture communicating channel 61 is indi-

cated and is such as to carry air and fiber from the discharge conduit 21 to the spaces to be filled, which are formed by the cabinet 46 and the dummy 60. The air thus introduced escapes through the screens of the dummy fixture 60 and is carried away from the apparatus, as by a connection inside the fixture to an opening 63 in the fixture 47, to which a conduit 64 is attached for discharge away from the filling station. The conduit 64 may have in it a gate valve like valve 25, arranged to operate with valves 25 and 26 by control 42.

For the purpose of controlling the foregoing mechanical equipment not only for normal operation with one or more automatic features, but also to protect it from abnormal or mischievous operation or accidental manipulations which might effect the operation, an electrical controlling arrangement is employed having interlocks and limit controls. Importantly, the lift 45 must not be lowered so as thereby to sever the connection between receptacle 46 and the fixture 47 while air is being delivered through conduit 21, either with or without suspended material being carried in the air stream. Consequently, arrangements are made so that the lift 45 may not be lowered while the one or both valves 25 and 26 are open. Likewise, arrangements are made so that the one or more valves 25 and 26 cannot be opened until the lift 45 is in operating position. Another feature is an arrangement whereby the material to be suspended, such as the fiber of bale 10, is not fed for suspension in air unless and until the gates or valves 25 and 26 are open and a suitable quantity of air is flowing through conduit 19.

Another feature is a cut-off control for the operation. When the operation is at an end, either by decision of an operator, or by register of an automatic means, there is a cut-off control which is arranged first to cut off the supply of fiber or like material 10, then, immediately or through a timing device set to allow sufficient time to permit the system to clear itself of fiber, to close the gates, thereby establishing circuits causing or permitting the lift 45 to be lowered. This cut-off control involves one or more of electrical switches so operated as to secure the above results.

The cut-off device may be manually operated or it may be operated by some functional condition of the operation being performed upon the receptacle 46. The particular cut-off illustrated and herein described is that which is described and claimed in the application of Duvall, Serial No. 713,428, filed December 2, 1946, now Patent No. 2,544,011. It is generally designated 70 in Fig. 1. It has been discovered that in the type of apparatus illustrated in Fig. 1, the end of the blowing corresponding to complete filling of the receptacle 46, is reflected by a quick change in differential pressure in the intake conduit 19.

The preferred embodiment of the invention combines in one control device both the readiness-responsive control and a cut-off control. In its described application the flow of air registers readiness by starting the feed of solids into the air stream and by taking the control away from the operator. In its cut-off function it stops the feed and initiates stopping the cycle.

At the beginning of an operation, even before feed of fiber 10 and when the gate valves are opened while the fan blower 20 revolves, there is a strong suction in the pipe 19. At the end of the operation with the receptacle 46 filled, the

said suction quickly reduces, and in some cases even reverses to a positive pressure by reason of a back-pressure effect from the blower resulting from substantial closure of its discharge end. Advantage is taken of this quick change in pressure in conduit 19 to actuate a pressure-responsive device. One way is to cause a damper to swing from a suction operated position to a normal or static position resistant to positive pressure or to low suction, according to the manner in which the damper is weighted or urged by its particular construction. The swinging of the damper between its two positions operates the cut-off device 70.

In Fig. 1 a lateral duct 19a is shown in the inlet conduit 19. At the end of the lateral duct 19a, there is indicated a damper 71 swinging on axis 12, and urged into normal and static position by means such as counterweight 73. The dotted line 74 represents a functional connection between the moving damper and the first-mentioned cut-off control 70. It is to be understood that the described control 70 is schematic for the purpose of convenience in description, and that the damper construction may be considered as part of the control 70. Manual means may also substitute for the action of the damper control. Numeral 75 is a schematic representation of manually operated means to register the cut-off point in the system, being effective to increase the urge of counterweight 73 to close the damper, as indicated by the arrow of said means 75.

In further provision of controls, there is provided a lift limit-control, preferably as a limit switch 76 arranged for actuation into one of two positions only when the lift is in operating position, whereby the response of the control or switch 76 effects the desired action. Preferably, switch 76 is closed when the lift is in operating position and open when the lift is out of operating position. For convenience in description, the device 76 is considered as a limit-control, either mechanical, or an electrical switch, and if the latter, either in the circuit to be controlled or in a relay circuit for the said circuit to be controlled. The position 76a is that occupied during operation.

One or both of the valves 25 and 26 may also be employed for operation of one or more limit-controls. Numerous expedients may be employed for causing the open or closed position of a gate valve to control one or more circuits. For convenience and to simplify the illustration, only gate valve 25 is provided with a limit-control designated 78, and it is to be understood that the diagrammatic control 78 may control one or more switches as will be explained with reference to the wiring diagrams. The gate limit-control 78 is indicated as having a movable bifurcated arm 79 in the path of a striker 80 on the gate stem 29. The arm 79 has its illustrated full-line position when the gate is closed, and when the gate is open it occupies dotted-line position 79a. It is clear that the exact locations and the separation of the bifurcated ends of operating arm 79, determine the degree of opening and of closure at which the limit control 78 operates. By the wide spacing shown, practically full opening and complete closure are the limits. However, since they may be changed and even reduced to a single responsive element, the operation is broadly considered to be upon opening and upon closure. However the parts are adjusted, the one or both gates should be completely closed before the lift can be lowered,

thereby to prevent air flowing into the atmosphere from the disconnected fixture and receptacle.

In order to explain the wiring diagrams, it is first pointed out that in practical applications of the system, there are relationships as between the receptacle 46 and fixture 47 which are of two characters. Sometimes the relationship is such that it is only necessary to bring the receptacle 46 to the fixture 47 without any manual manipulation before blowing can be started. In other circumstances it is necessary to bring the receptacle to the fixture, and then to make some mechanical adjustment by an operator, before the blowing can take place. In the latter instance it is usually necessary that a manual operation also be accomplished after the blowing and before the receptacle and fixture can be separated. Therefore, in the electrical arrangements, the controls are so devised and connected with the provision of manual push-buttons that the device may be operated as follows:

Full-automatic.—When blowing can begin as soon as the receptacle 46 is raised to the fixture 47 it is only necessary for the operator to hold depressed one push-button switch to cause the lift 45 to rise. For safety, it is arranged that the button be held depressed until a predetermined condition is attained, thereby causing an earlier release of the button to reverse the lift. The button is held depressed until the lift 45 is in raised position and thereby through the effect of the limit control 76, a switch is closed causing the blast gates in conduits 19 and 21 to open and thereby operate limit control 78. The latter is arranged to function so that the said starting push-button switch is by-passed to hold the lift raised and to permit the operator to release the starting button. When the blast gates are open sufficiently at least to cause adequate suction in conduit 19, the damper 71 swings inward and affects cut-off control 70, arranged then to permit fiber 10 to be fed into the system. The operation proceeds until the cut-off control 70 is operated or automatically functions to cut-off, and the results are to stop the feed of fiber 10, and to control a circuit, immediately or through a time control, permitting the gates to close. Upon closure of the gates, the gate limit-control 78 establishes conditions which then cause the lift 45 to be lowered. Thus, the equipment is in position for a repetition of this cycle.

Semi-automatic.—When an operation must be performed on the raised receptacle 46 before blowing, the first operation is a manual one of pressing the starting push button to raise the lift 45 as in the full-automatic system. But, upon attaining the raised position of the lift the lift limit-control 76 effects the holding by-pass of the manual starting switch thereby to hold the lift raised and to permit the operator to release the starting button. Also the lift limit-control 76 functions to control a circuit so that only thereafter may the circuit be manually closed to open the blast gates. Before thus opening the blast gates the manual operation required at the receptacle 46 is performed and then a second manual push button is depressed which causes the blast gates to open but only while said button is being depressed. When the blast gates are sufficiently open the gate limit-control 78 functions to by-pass the lift-raising switch closed by the lift limit-control 76 so that the lift must stay up until the gates are closed. When the gates are open sufficiently to create suction to

operate the cut-off control 70, the latter effects a by-pass of the manual gate-opening switch permitting the gates to remain open and permitting the starting button for the gates to be released. Additionally the cut-off control 70 operates to permit the fiber 10 to be fed to the system. If desired, the gate limit-control can operate to prevent by-passing of the gate-starting button and to prevent feed, until the gates are fully open. Then blowing continues until cut-off is established, preferably by automatic cut-off damper 11 acting on the cut-off control 70. The cut-off control 70 automatically stops the feed of fiber and initiates closure of the blast gates. Closure of the gates is effective through the gate limit-control 78 to establish conditions permitting thereafter a manual operation to drop the lift 45, thereby to restore the system to normal. Said last-mentioned manual operation is necessary in order to prevent automatic drop of the lift 45 until such time as the required manual manipulations at the filling station as to the receptacle 46 have been performed.

As described herein the circuits are arranged so that the said full-automatic control or the said semi-automatic control may be employed at will by operating a circuit-shifting control which changes the effective connections so that either one system or the other is operative. In the following explanation of the wiring diagrams, only the bare essentials and fundamental circuits are disclosed. It is to be understood that additional signals and safety arrangements may be added as desired, and relay-operated switches interposed, without departing from the principle of the operation.

Fig. 2 represents the basic circuit and control arrangement for the full-automatic system. Numerals 101 and 102 represent power supply lines. Between these there is a circuit comprising in series the lift-operating means 58 (for controlling air-valve 53 in Fig. 1) connected at one side to line 102 and on the other side to an electrical connection 103 leading to a manually operated switch 104, thence through electrical connection 105 and thence through normally closed manually openable switch 106 to the power line 101. Thus, upon manual closure of the switch 104 the circuit is energized to raise the lift. The switch 104 must be manually closed to hold the lift elevated until further action ensues. A limit switch 107 is connected from the main line 101 to the connection 103 thereby effecting a shunt around the manual switch 104 permitting switch 104 to be opened after switch 107 is closed, thereby to hold the lift raised. Switch 107 is arranged to be closed by action of the gate limit-control 78 when the gates are open.

The gate-operating control 42 (for the valve 39 in Fig. 1) is connected at one side to the power line 102 and at the other side through connection 109 to a second manual switch 110, thence through connection 111 to a limit switch 112, and thence to connection 115. The switches 104 and 110 are mechanically interconnected for opening and closing together as by operating an associated push button 113 normally urged to open said switches and requiring manual depression to close said switches. Thus, it will be seen that closure of switch 110 (along with switch 104) does not effect opening of the gates unless limit switch 112 is closed. Limit switch 112 is associated with the lift limit-control 78 to be closed only when the lift is in raised position. Thus, upon closure by

pressing push button 113 the lift rises and upon reaching uppermost position it closes switch 112 causing the gate control 42 to initiate opening of the gates. This continues until the gates are sufficiently open when the limit switch 107 is closed by limit-control 78 thus permitting the lift to remain up when push button 113 is released. However, releasing the push button 113 will open switch 110, and thus would cause the gates to close except that there is by-pass around said switch 110 which will have in the meantime been closed. This by-pass is represented by the connection 115 beginning in the connection 111 and by the connection 116 beginning in connection 109, both connections 115 and 116 leading to a switch 118 which is normally open until the system attains an air flow sufficient to cause suction to move cut-off control 70. Switch 118 which is normally open, is closed by suction operating through cut-off control 70 and when closed is opened by the cut-off control 70 at the cut-off point. Hence, push button 113 is held until switch 118 is closed. A signal lamp 130 under suitable control may light, as shown in Fig. 2b. Thus, it will appear that at the end of a blowing operation when the push button 113 will have been released, the cut-off operation opens switch 118, thereby breaking the circuit which holds the gates open, causing them to close, and then when closed to cause the lift to drop.

However, the operation intended to be controlled requires the feed of fiber 10 to it in order to attain a cut-off point. The device indicated at 120 is a means which when energized initiates the feeding of fiber 10 into the system, as by control of power means 14 in Fig. 1. The feed control 120 is connected at one side of the main line 102 and at the other side by connection 121 through a switch 122 to the said connection 115. Switch 122 is a switch functioning the same as switch 118, that is, being likewise related to the cut-off control 70 so as to be normally closed during an operation and being open at and after cut-off.

The manually openable switch 106 is provided for emergency control. In the beginning of a cycle while push button 113 must be pressed to initiate and maintain the first stages of the cycle, mere release of push button 113 will open switches 104 and 110 as stopping controls for any emergency. After switch 107 cuts out switch 104 and permits automatic continuation of the cycle, the push button 106 may be pressed to open switch 106. This will not immediately affect the platform 58 which must remain in set position until the valve gates are closed; but it will de-energize the valve-control mechanism 42 to cause the gates to close, and also it will de-energize the feeding means 120. Not until the gates close, will switch 107 open to de-energize the station-control means and thus move the platform 58 from receiving to idle position. The opening of manual switch 106 has the same effect as mechanical cut-off through means 75 in Fig. 1. Hence, switch 106 is also a manual cut-off control.

In Fig. 2 there is a broken line 123 indicating a division line in the diagram. In Figs. 2a and 2b there are respectively similar broken lines 123a and 123b. By considering line 123 and 123a superimposed to lay Fig. 2a over a part of Fig. 2, a modified circuit is indicated. Similarly a modified circuit is shown by considering line 123b similarly superimposed on line 123. Fig. 2a represents a modification of the circuit of Fig. 2 with

the additional inclusion of a switch 125 in the connection 115 of Fig. 2, which connection is indicated in two parts in Fig. 2a, as 115a and 115b. Switch 125 operates the same as the switch 101, and is under the control of the gate limit-control device 78, so that the switch 125 is open when the gate is closed and closed when the gate is open. In Fig. 2 the circuit 115 leading to the feed control 120 is energized as soon as the lift causes closure of switch 112, and the circuit 121 leading to the feed control 120 is energized as soon as sufficient suction operates the cut-off control 70. By insertion of the switch 125 in this connection, the feed cannot operate until the gates are as fully open as the control 78 is set for.

In Fig. 2b a modification of the arrangement of Fig. 2a is shown in which the described control of Fig. 2 between the cut-off control 70 and the switch 118 is modified by use of a time relay to delay the opening of switch 118. To accomplish this, a solenoid 127 is placed in parallel with the feed control 120, and the solenoid acts through an association or conventional device indicated at 128, to time the opening of switch 118, and hence to delay initiation of closure of the gates for a short time after stopping the feed control 120, thereby to clean the system of residual fiber.

Also Fig. 2b illustrates an optional addition of a signal lamp 130 in parallel with the feed control 120. The signal lamp may, therefore, be placed on a control board along side the push button 113 to signal the operator that full operation has been initiated, whereby the operator may release button 113 to let the cycle continue, then stop, and then reset itself automatically.

Fig. 3 is directed to the circuits for semi-automatic operation of the device. Although some of the switches and circuits in Fig. 3 are the same as have been particularly designated in Fig. 2, Fig. 3 is herein described independently of Fig. 2 as to the identification of parts, but not as to the controls or devices brought into the wiring diagrams from Fig. 1, the same numerals for these being employed in Figs. 1, 2 and 3.

The power lines are designated 133 and 134. The lift operating mechanism 58 is connected at one side to the main 134 and on the other side by a connection 140 to a normally open manually held closed switch 141, operated by pressing on an associated push button 142. The other side of switch 141 runs through connection 143 to one side of a normally closed manually openable switch 144 which is connected on its other side to main 133. By-passing both switches 144 and 141 is a limit switch 145 connected to the main 133 and to the connection 140. Switch 145 is arranged to be closed when the gates are open, and open when the gates are closed, and operation of the switch 145 is effected through the gate limit-control 78. By-passed around switch 141 is a limit switch 147 connected to the said connections 140 and 143. Switch 147 is open when the lift 45 is down and is closed when the lift 45 is in operating position. To accomplish this, switch 147 is associated with the lift limit-control 76 for its operation. Thus, it will be seen that when the push button 142 is held depressed, the lift 45 rises to operating position, and upon attaining operating position, switch 147 is closed thereby to lock or hold the lift in raised position and to permit the operator to release push button 142. Nothing further happens until a second manual control is effected, thus permitting a manual operation to be performed at the filling station.

Assuming the manual operation to have been performed to make the filling station ready for blowing, a second push button 150 is held depressed. This closes switch 151 which is connected on one side through connection 152 to the gate operating device 42 to the power line 134, and on the other side through connection 153 to a normally closed manually openable switch 154, thence through a limit switch 155 to the connection 143. Switch 155 is arranged to be opened when the lift is down and closed when the lift is in operating position, and hence it is under control of the lift limit-control 76. Around the push-button switch 151 is a switch 157 which is normally closed during operation by air-flow control acting on cut-off device 70, and arranged to be opened by the cut-off device 70. From the connection 153 there is a connection 158 through switch 159, thence through feed control 120 to main line 134. Switch 159 operates along with switch 157 and is under similar controls by the cut-off 70.

By following the circuits above described it will be seen that when the prepared receptacle is ready for blowing by having been raised on the lift to the set position, and after having had performed any necessary work on it, the manual push button 150 is depressed establishing energization of the gate-opening means 42.

When the gates are sufficiently open there will be flow of air and suction to actuate the cut-off control 70 to close switches 157 and 159, as a result of which, respectively, the button 150 may be released, and the feed 120 will operate. Upon continuance of operation to the point of cut-off, the switches 159 and 157 will open resulting, respectively, in cutting off the feed and cutting off energy to the gate-opening mechanism whereby the latter will begin to close. The circuit to the lift-raising mechanism remains energized and cannot be de-energized until the gates are closed by the resulting opening of switch 145. However, the opening of switch 145 does not lower the lift, because the lift holds itself up by closure of locking switch 147, which is under the control of manual switch 144. Therefore, the lift may be lowered only by manually opening switch 144, but this cannot be effective unless the gates are closed with resultant opening of switch 145.

The manual switch 154 is an emergency control switch, or may function as a manual register of the cut-off point, and it is normally closed. Opening it will effect immediately the stopping of the feed 120 and initiate closing of the gates by de-energizing mechanism 42.

Figs. 3a and 3b show modifications in the circuits of Fig. 3, which are the same as shown by Figs. 2a and 2b. The broken line 160 in Fig. 3 indicates a division line in the diagram. The same line appears in Figs. 3a and 3b. By superimposing either Fig. 3a or Fig. 3b on Fig. 3 with coincidence of the lines 160, the modification is obvious.

Fig. 3a repeats the component parts of Fig. 3 with the change of connection 158 of Fig. 3 to two connections 158a and 158b and with interposition of a gate limit switch 161 between them in a manner to control both switches 157 and 159. Switch 161 is normally open and is closed by gate control 78 in the opening of the gate or gates, along with similar control of switch 145 for the lift 58.

Fig. 3b includes modifications additional to that of Fig. 3a. These additions may be used with or without the switch 161, which is an optional

protective device. The chief modification is to effect a delay in opening switch 157 by and after the operation of cut-off control 70. This is effected by interposing a delay relay to control switch 157. Numeral 162 represents a solenoid for such a delay relay, and it is in parallel with feeding device 120. Numeral 163 represents the relay-association to effect snap closure and delayed opening of switch 157, respectively by energizing and de-energizing solenoid 162. Also in parallel with feeding device 120 is a signal device, preferably a lamp 164, which is lighted when the feeding device 120 operates. When placed in view of the operator, its lighting signifies end of the starting operation. When lamp 164 lights, it is due to device 70 closing switch 159, and through solenoid 162 also closing switch 157 thereby to by-pass push-button switch 151 taking control of the gates away from the operator. Practically, the lighting of lamp 164 is a signal to the operator to release the push-button switch 151.

From the foregoing description it is clear that after the cut-off device 70 operates the receptacle 48 cannot be separated from the fixture 47 except by manually opening switch 144, which opening is delayed until the required mechanical operation has been performed.

Fig. 4 represents a wiring diagram in which the circuits of Fig. 2 and Fig. 3 may be alternatively selected. After an understanding of the circuits of Fig. 2 and of Fig. 3, the combined circuits may be readily understood, and are hence only briefly described. The power lines are designated anew as 165 and 166. Connected to the line 166 in parallel are the lift control mechanism 58, the gate control mechanism 42, and the feed control mechanism 120. The lift control mechanism 58 is connected to junction 168. Gate control mechanism 42 is connected to junction 169. Feed control 120 is connected through a switch 170 to junction 171. Between main line 165 and junction 168 is a switch 172 closed by the gate limit-control 78 on opening of the gates. There is a spring-opposed push button 174 which is depressed to close two normally opened switches 175 and 176. Switch 175 is connected on one side to the junction 168, and on the other side is connected to a junction 177 and therefrom through a switch 178 to power line 165. Switch 178 is normally closed and manually openable. There are also two other manually controlled and related switches 180 and 181 of which one is closed when the other is open. Operation of these two switches by a single manual control indicated at 182 effects a shifting of the system from the full automatic control of Fig. 2 to the semi-automatic control of Fig. 3. Switch 180 is connected on one side to the junction 168 and on the other side to a switch 184, the other side of which is connected to junction 177. Switch 184 is a limit switch closed by the lift limit-control 76. There is also another switch 185 likewise controlled by the lift limit-control 76. Switch 185 is connected on one side to the junction 177 and on the other side to a switch 186 normally closed and manually openable of which the other side is connected to junction 187. Numeral 188 is a push-button type of switch normally opened and manually held closed for opening the gates, connected on one side to the junction 181 and on the other to the junction 169, thus serving as a starting switch for the blowing operation after preparing the station, and comparable to switch 151 in

Fig. 3. The switch 176, under control of the starting push-button 174, is connected on one side to junction 187 and on the other side to one side of switch 181 which on the other side is connected to junction 169. There is a connection 190 between the junctions 171 and 187. Interposed between the junctions 171 and 169 is a switch 191. Said switches 191 and 170 are actuated by the cut-off device 70, and are the same in function as the switches 157 and 159 in Fig. 3 and the switches 118 and 122 in Fig. 2.

Figs. 4a and 4b represent modifications of the circuits of Fig. 4, to be read by considering the broken lines 192a and 192b of Fig. 4a and Fig. 4b superimposed on a similar line 192 in Fig. 4. These modifications are the same as already described for Figs. 2 and 3, with the difference that Fig. 4b does not include the modification of Fig. 4a. It is to be understood that either one or both of the modifications of Figs. 4a and 4b may be used at the same time.

Fig. 4a shows connection 190 of Fig. 4 changed to connection 190a, gate-limit control switch 193, and connection 190b. Switch 193 is normally open when the gates are closed and is closed by the device 78 operated by the opening gates.

Fig. 4b places in parallel with the feeding device 120 a solenoid 195 of a delay relay which is represented at 196 as a conventional arrangement to close switch 191 upon energizing the solenoid 195 and to delay opening switch 191 upon energizing the solenoid 195 and to delay opening switch 191 after de-energizing solenoid 195. Numeral 197 represents a signal, such as a lamp to light when the feeding device 120 is in operation, the lamp being under the same control as by being in parallel with the device 120.

When the manual control 182 is in the full-line position shown to open switch 180 and close switch 181 the circuits thereby selected are those of Fig. 2. When the position is changed so that switch 180 is closed and switch 181 is open, the circuits selected are those of Fig. 3.

It will thus be seen from the foregoing description and explanation that the mechanical equipment illustrated in Fig. 1 is capable of simple operation and of ready operation to a variety of fixture relationships permitting either full automatic operation or requiring semi-automatic operation as described.

Numerous changes and modifications are contemplated in the appended claims.

I claim:

1. In a system having a fluid delivery under control of valve means and a movable device at a delivery station which device has a set position for accepting delivery when said valve means is open and which device is movable from set position to idle position, electrical station-control means arranged when energized to move said device from idle to set position, electrical valve-control means arranged when energized to move said valve means from closed to open position, a manual starting switch arranged for manually held closure to energize said station-control means, a holding switch around said starting switch arranged for closure only upon open status of said valve means, and an electrical switch normally open and arranged when open to prevent energizing said valve-control means to open said valve means and arranged for closure only when said device is in set position.
2. In a system having a fluid delivery under control of valve means and a movable device at

a delivery station which device has a set position for accepting delivery when said valve means is open and which device is movable from set position to idle position, electrical station-control means arranged when energized to move said device from idle to set position, electrical valve-control means arranged when energized to move said valve means from closed to open position, a manual starting switch arranged for manually held closure to energize said station-control means, a holding switch around said starting switch arranged for closure only upon open status of said valve means, and an electrical switch normally open and arranged when open to prevent energizing and when closed to energize said valve-control means to open said valve means and arranged for closure only when said device is in set position.

3. In a system having a fluid delivery under control of valve means and a movable device at a delivery station which device has a set position for accepting delivery when said valve means is open and which device is movable from set position to idle position, electrical station-control means arranged when energized to move said device from idle to set position, electrical valve-control means arranged when energized to move said valve means from closed to open position, a manual starting first switch arranged for manually held closure to energize said station-control means, a holding second switch around said starting switch arranged for closure only upon open status of said valve means, a third electrical switch normally open and arranged when open to prevent energizing said valve-control means to open said valve means and arranged for closure only when said device is in set position, and a manually controlled fourth switch to effect energizing of said valve-control means through the closed third switch.

4. In a system having a fluid delivery under control of valve means and a movable device at a delivery station which device has a set position for accepting delivery when said valve means is open and which device is movable from set position to idle position, electrical station-control means arranged when energized to move said device from idle to set position, electrical valve-control means arranged when energized to move said valve means from closed to open position, a manual starting switch arranged for manually held closure to energize said station-control means, a holding switch around said starting switch arranged for closure only upon open status of said valve means, and an electrical switch normally open and arranged when open to prevent energizing said valve-control means to open said valve means and arranged for closure only when said device is in set position and for closing and opening operation by movement of said device respectively into and out of set position.

5. In a system having a fluid delivery under control of valve means and a movable device at a delivery station which device has a set position for accepting delivery when said valve means is open and which device is movable from set position to idle position, electrical station-control means arranged when energized to move said device from idle to set position, electrical valve-control means arranged when energized to move said valve means from closed to open position, a manual starting switch arranged for manually held closure to energize said station-control means, a holding switch around said starting

switch arranged for closure only upon open status of said valve means, and an electrical switch normally open and arranged when open to prevent energizing and when closed to energize said valve-control means to open said valve means and arranged for closure only when said device is in set position and for closing and opening operation by movement of said device respectively into and out of set position.

6. In a system having a fluid delivery under control of valve means and a movable device at a delivery station which device has a set position for accepting delivery when said valve means is open and which device is movable from set position to idle position, electrical station-control means arranged when energized to move said device from idle to set position, electrical valve-control means arranged when energized to move said valve means from closed to open position, a manual starting switch arranged for manually held closure to energize said station-control means, a holding switch around said starting switch arranged for closure only upon open status of said valve means, an electrical switch normally open and arranged when open to prevent energizing said valve-control means to open said valve means and arranged for closure only when said device is in set position and by movement of said device to set position, and a manually controlled switch to complete the energizing of said valve-control means.

7. In a fluid discharging system having a fluid supply, valve means in said supply, and a movable device at a station for association with said supply which device receives fluid in a set position of the device and which is movable from said set position to an idle position, in combination, station-control means energized to move the device to and hold it in set position from idle position, valve-control means energizable only in the set position of the device to open the valve means, and holding means associated with the valve means and arranged to energize said station-control means in the open position of said valve means.

8. In a fluid discharging system having a fluid supply, valve means in said supply, and a movable device at a station for association with said supply which device receives fluid in a set position of the device and which is movable from said set position to an idle position, in combination, station-control means energized to move the device to and hold it in set position from idle position, valve-control means arranged to be energized to open the valve means by action of the device when it reaches set position, and holding means associated with the valve means and arranged to energize said station-control means in the open position of said valve means.

9. In a fluid discharging system having a fluid supply, valve means in said supply, and a movable device at a station for association with said supply which device receives fluid in a set position of the device and which is movable from said set position to an idle position, in combination, station-control means arranged when energized to move the device to and hold it in set position from idle position, a manually held switch arranged when closed to energize said station-control means, valve-control means arranged when energized to open the valve means, a second manually held switch arranged when closed to permit energizing said valve-control means, a controlling switch in a circuit containing said second manually held switch and said valve-

control means arranged to be open when the device is out of set position and to be closed when said device is in set position, a switch associated with the valve means and arranged to by-pass said first manual switch to energize said station-control means in the open position of said valve means.

10. In a fluid discharging system having a fluid supply, valve means in said supply, and a movable device at a station for association with said supply which device receives fluid in a set position of the device and which is movable from said set position to an idle position, in combination, station-control means energized to move the device to and hold it in set position from idle position, valve-control means energizable only in the set position on the device to open the valve means, holding means associated with the valve means and arranged to energize said station-control means in the open position of said valve means, manually holdable means to be held to energize the station-control means until the valve means is open, and means for de-energizing the valve-control means whereby on resulting closure of the valve means the said holding means is rendered inoperative thereby to permit de-energizing the station-control means with resulting return of the device to idle position.

11. In a fluid discharging system having a fluid supply, valve means in said supply, and a movable device at a station for association with said supply which device receives fluid in a set position of the device and which is movable from said set position to an idle position, in combination, station-control means energized to move the device to and hold it in set position from idle position, valve-control means arranged to be energized to open the valve means when the device reaches set position, holding means associated with the valve means and arranged to energize said station-control means in the open position of said valve means, manually holdable means to be held to energize the station-control means until the valve means is open, and means for de-energizing the valve-control means whereby on a resulting closure of the valve means the said holding means is rendered inoperative and de-energizes the station-control means whereby said manual means may be released from energizing position.

12. In a fluid discharging system having a fluid supply, valve means in said supply, and a movable device at a station for association with said supply which device receives fluid in a set position of the device and which is movable from said set position to an idle position, in combination, station-control means energized to move the device to and hold it in set position from idle position, valve-control means for energization to open the valve means and arranged to prevent its energization except when the device is in set position, manually holdable means to be held to energize the station-control means until the device is in set position, means bypassing said manually holdable means and rendered operative to energize the station-control means when the device is in set position, whereby said manually holdable means may be released, a manually closable switch to effect energizing said valve-control means to open the valve means, means by-passing said last-mentioned switch to energize said valve control means for opening the valve means and arranged to be rendered operative by a flow of fluid resulting from opening the valve means, means arranged inde-

pendently of said first-mentioned by-passing means to energize said station-control means by the valve means when in open position, means for de-energizing the valve-control means, whereby on resulting closure of the valve means said independent energization of the station-control means is cut off leaving energization thereof through said first-mentioned by-passing means, and manual means to de-energize the station-control means whereby the device returns to idle position.

13. In combination, electrically powered feeding means arranged when energized continuously to feed particle form material into an air stream, a power-operated fan blower arranged for continuous operation and for creating said moving air stream, conduit means connected to said blower including a delivery conduit for carrying and discharging a suspension of said particles in air, flow-responsive means having one position during a predetermined extent of flow of air in said conduit and another position upon substantial reduction of said predetermined flow, a movable device at a receiving station at the discharge end of said conduit, said movable device being arranged to move into a set position for receipt of said suspension and to move therefrom to an idle position, electrical station-control means arranged when energized to move and hold the device to and in set position and when de-energized to move the device to idle position, valve means in said conduit means arranged for opening and closure to permit and to stop the flow of air and of suspension in said delivery conduit, electrical valve-control means arranged when energized to open said valve means and when de-energized to close said valve means, manually controlled means for energizing the station-control means, means under control of the device to prevent energizing the valve-control means except in the set position of the device, a second manually controlled means for energizing the valve-control means, means under control of the open valve means to maintain energization of the station-control means, means under control of said flow-responsive means acting in said position at the predetermined flow to maintain energization of the valve-control means after release of the second manually controlled means and acting upon said reduction of said flow to de-energize the valve-control means, and feed-control means under control of the pre-determined flow to energize the feeding means and upon said reduction of said flow to de-energize said feeding means.

14. In combination, electrically powered feeding means arranged when energized continuously to feed particle form material into an air stream, a power-operated fan blower arranged for continuous operation and for creating said moving air stream, conduit means connected to said blower including a delivery conduit for carrying and discharging a suspension of said particles in air, flow-responsive means having one position during a predetermined extent of flow of air in said conduit and another position upon substantial reduction of said predetermined flow, a movable device at a receiving station at the discharge end of said conduit, said movable device being arranged to move into a set position for receipt of said suspension and to move therefrom to an idle position, electrical station-control means arranged when energized to move and hold the device to and in set position and when de-energized to move the device to idle

position, valve means in said conduit means arranged for opening and closure to permit and to stop the flow of air and of suspension in said delivery conduit, electrical valve-control means arranged when energized to open said valve means and when de-energized to close said valve means, manually controlled means for energizing the station-control means, means under control of the device to prevent energizing the valve-control means except in the set position of the device, a second manually controlled means arranged to operate simultaneously with the first manually controlled means to clear a channel for energization of the valve-control means, means under control of the open valve means to maintain energization of the station-control means, means under control of said flow-responsive means acting in its said position at the predetermined flow to maintain energization of the valve-control means after release of the second manual control switch and acting upon said reduction of said flow to de-energize the valve-control means, and a circuit to said feeding means under control of the predetermined flow to energize the feeding means and upon said reduction of said flow to de-energize said feeding means.

15. In combination, electrically powered feeding means arranged when energized continuously to feed particle form material into an air stream, a power-operated fan blower arranged for continuous operation and for creating said moving air stream, conduit means connected to said blower including a delivery conduit for carrying and discharging a suspension of said particles in air, flow-responsive means having one position during a predetermined extent of flow of air in said conduit and another position upon substantial reduction of said predetermined flow, a movable device at a receiving station at the discharge end of said conduit, said movable device being arranged to move into a set position for receipt of said suspension and to move therefrom to an idle position, electrical station-control means arranged when energized to move and hold the device to and in set posi-

tion and when de-energized to move the device to idle position, valve means in said conduit means arranged for opening and closure to permit and to stop the flow of air and of suspension in said delivery conduit, electrical valve-control means arranged when energized to open said valve means and when de-energized to close said valve means, a manually controlled switch for one channel for energizing the station-control means, a switch under control of the device to prevent energizing the valve-control means except in the set position of the device, a second switch under control of the set device to maintain a second channel of energization of the station-control means whereby to permit release of said manually controlled switch, an independent manual control switch to energize the valve-control means, a switch under control of the open valve means to maintain a third channel of energization of the station-control means, a switch under control of said flow-responsive means acting in its said position at the predetermined flow to maintain energization of the valve-control means after release of the independent manual control switch and acting upon said reduction of said flow to de-energize the valve-control means, a circuit to said feeding means under control of the predetermined flow to energize said feeding means and upon said reduction of said flow to de-energize said feeding means, and a switch for independent manual operation to de-energize said second channel of energization for station-control means whereby to move said device into idle position from set position.

Certificate of Correction

Patent No. 2,576,543

November 27, 1951

JUDSON P. SMITH

It is hereby certified that error appears in the printed specification of the above numbered patent requiring correction as follows:

Column 3, line 23, for "article" read *particle*; column 5, line 17, for "corresponding" read *correspondingly*; column 8, line 20, for "devised" read *devised*; column 14, lines 33 and 34, strike out "upon energizing the solenoid 195 and to delay opening switch 191"; line 48, for "operation", second occurrence, read *adaptation*; column 17, line 17, for "position on" read *position of*; line 46, after "on" strike out "a";

and that the said Letters Patent should be read as corrected above, so that the same may conform to the record of the case in the Patent Office.

Signed and sealed this 4th day of March, A. D. 1952.

[SEAL]

THOMAS F. MURPHY,
Assistant Commissioner of Patents.
